UNITED STATES PATENT OFFICE

JAMES D. HUMPHREY, OF McALESTER, OKLAHOMA

FLORAL STAND

Application filed December 31, 1927. Serial No. 243,891.

This invention relates to a floral stand and has for its primary object the construction of a collapsible stand and may be collapsed to occupy a minimum space but may be readily extended in positions to conform to the contour of an article associated therewith and provided with a plurality of supports, hangers, or supporting pins whereby articles can be properly and artistically supported.

10 An object of the invention is the construction of a floral stand particularly adapted for use with caskets for supporting the floral pieces in their most advantageous position relative to the casket and further to provide a 15 pleasing background for the casket.

Another object of the invention is the construction of a stand of a plurality of parts or sections so connected together that they may be readily folded into a predetermined arrangement with each other to provide a very compact article for transportation from place to place.

Another object of the invention is the novel manner of arranging the supporting pins 25 contiguous to a plurality of openings so that when the various sections are folded into their proper relations with each other, the pins may be allowed to project through the openings so as to minimize space.

30 With these and other objects in view, the invention will be better understood from the following detailed description taken in connection with the accompanying drawings, wherein:

35 Figure 1 is a front elevation of the stand set up,

Figure 2 is an edge elevation showing the parts bolted,

40 Figure 3 is a top plan view,

Figure 4 is an end elevation,

Figure 5 is an end elevation in folded position,

45 Figure 6 is an enlarged sectional view portion of the stand,

Figure 7 is a rear elevation of one end of the stand,

50 Figure 8 is a detailed view illustrating the interlocking connection between certain sections, and

Figure 9 is an elevation of one of the end sections in folded position.

Again referring to the drawings illustrating one of the many constructions of my invention and more particularly to Figure 1 it 55 will be noted that the invention consists of the end sections 1 and 2 and intermediate section 3, so connected and constructed that the end sections may be readily set up and the intermediate section extended for providing 60 the proper arrangement of a plurality of hangers or supporting pins for supporting articles such as floral pieces.

The end sections 1 and 2 which are identical in construction and hereinafter known as 65 supporting frames, each consists of an upper section 4 and a lower section 5 hinged together as indicated at 6 so that they may be folded into parallel relation with each other or to be extended in alignment with each other as shown in Figure 1. These supporting frames are held in a slightly inclined vertical position by the brace structure 7 that has a hinged connection 8 with the lower section and provided with foldable strut 9 which 70 when extended prevent accidental collapsing of the brace structure.

The intermediate section or support 3 is of angular formation in plan, and the central portion 3^a thereof is arranged in a plane located beyond the end sections 1 and 2. The end portions 3^b of the intermediate section 3 extend forwardly and outwardly from the central portion 3^a to the end sections 1 and 2, and the respective pairs of end portions and 80 end sections are arranged in common planes. The intermediate section 3 consists of an upper bar member 10 and a lower bar member 11 each of which consists of a plurality of sections 12 having a hinged connection 13 with 85 each other so as to be capable of folding into parallel relation with each other. The end sections 14 of the bar members are secured to the end frames by the braces 15 that have a detachable connection with the end frames 90 and also by means of locking links 16 that also have interlocking connection with the end frames. This construction enables the supports to be entirely disconnected from the end frames to facilitate folding of the same 95 100

and to enable the easy collapsing of the end frames.

It is, of course, to be understood that by folding the intermediate section and the end sections independently the time for setting up and collapsing the stand is materially reduced and besides the parts may be more readily conveyed from place to place.

Each of the end frames and also the intermediate section of supports have projecting therefrom a plurality of hangers or supporting pins 17 for supporting floral pieces thereon and to minimize space each hanger or pin has associated therewith an opening 18 for the reception of a pin when the parts are folded into parallel relation with each other. An advantage of this arrangement is that the pins are completely housed within the sections thereby fully protecting the pins and enabling the parts to come into closer relation with each other to minimize space. The stand is of angular formation in plan, and the end sections 1 and 2 and the intermediate section 3 thereof are supported in an upwardly and rearwardly inclined position, to permit a large number of flowers to be displayed in a comparatively narrow space and to permit the flowers to be displayed in a manner to render each clearly visible.

From the foregoing description taken in connection with the accompanying drawings, it will be appreciated that I have constructed a device that may be readily extended to assume various angular positions and to conform to the contour of various articles associated therewith. It will be appreciated also that floral pieces may be more effectively displayed in such a manner to provide a very pleasing background for the casket.

It is, of course, to be understood that the end sections as well as the intermediate section may be constructed and designed in various other manners than illustrated and connected together in other relations and various other types of supporting devices may be utilized therewith, and therefore, I do not desire to be limited in protection in any manner whatsoever, except as set forth in the following claims.

What I claim is:

1. A stand comprising end frames arranged in laterally spaced and angularly related planes and adapted to rest in their lower ends upon the ground, a bar having a central portion located rearwardly of the frames and having end portions extending forwardly and laterally from the central portion to the frames, braces extending downwardly and rearwardly from the frames to the ground to support the frames and the bar in an upwardly and forwardly inclined position, and article supporting elements secured to the frames and bar.

2. A stand comprising end frames arranged in laterally spaced and angularly re-

lated planes and adapted to rest at their lower ends upon the ground, each frame consisting of upper and lower sections hinged together to permit them to be folded one against the other, a bar having a central portion located rearwardly of the upper frame sections and having end portions extending forwardly and laterally from the central portion to the upper frame sections, hinges connecting the central and end portions of the bar to permit these parts to be folded one against the other, means detachably connecting the end portions of the bar to the upper frame sections, braces extending downwardly and rearwardly from the lower frame sections to the ground and adapted to support the frames and bar in an upwardly and forwardly inclined position, hinges connecting the braces to the lower frame sections to permit the braces to be folded against said sections, and article supporting elements secured to the frames and bar.

In testimony whereof I affix my signature.
JAMES D. HUMPHREY.
